CLAIM

The ornamental design for a recreational flotation device, as shown and described.

DESCRIPTION

FIG. 1 is a perspective view of a recreational flotation device in accordance with our new design.

FIG. 2 is a top plan view of the recreational flotation device of FIG. 1.

FIG. 3 is an elevational view as seen from the lower edge of FIG. 2.

FIG. 4 is a bottom plan view.

FIG. 5 is an elevational view as seen from the left edge of FIG. 2; and,

FIG. 6 is an elevational view as seen from the right edge of FIG. 2.
